UNITED STATES PATENT OFFICE.

WILLIAM G. MOORE, OF OMAHA, NEBRASKA.

DESIGN FOR AN INVERTIBLE DESK CABINET.

Application filed July 25, 1921. Serial No. 487,213. Term of patent 3½ years.

To all whom it may concern:

Be it known that I, WILLIAM G. MOORE, a citizen of the United States, and a resident of Omaha, in the county of Douglas and State of Nebraska, have invented a certain new, original, and ornamental Design for Invertible Desk Cabinet, of which the following is a specification, reference being had to the accompanying drawings, forming a part hereof.

The figure is a perspective view of a desk cabinet, showing my design, the cabinet being closed.

I claim:

The ornamental design for an invertible desk cabinet, as shown.

W. G. MOORE.
